Primary Examiner — Ania Aman

(57) **CLAIM**

The ornamental design for a grill, as shown and described.

DESCRIPTION

FIG. 1 is a front elevational view of a grill showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof;

FIG. 8 is an enlarged view of the grill taken from the circle part in FIG. 1;

FIG. 9 is another enlarged view of the grill taken from the circle part in FIG. 1;

FIG. 10 is an enlarged view of the grill taken from the circle part in FIG. 2;

FIG. 11 is an enlarged view of the grill taken from the circle part in FIG. 5; and,

FIG. 12 is an enlarged view of the grill taken from the circle part in FIG. 6.

The broken lines identifying the enlarged views form no part of the claimed design.
